Primary Examiner — Elizabeth A Albert(74) *Attorney, Agent, or Firm* — Harness, Dickey & Pierce, P.L.C.(57) **CLAIM**

The ornamental design for an electronic vapor kit, as shown and described.

DESCRIPTION

FIG. 1 is a front, right perspective view of an electronic vapor kit showing our new design;

FIG. 2 is a top plan view thereof.

FIG. 3 is a bottom plan view thereof.

FIG. 4 is a front elevational view thereof.

FIG. 5 is a rear elevational view thereof.

FIG. 6 is right elevational view thereof.

FIG. 7 is a left elevational view thereof.

FIG. 8 is a front, right perspective view thereof in an open configuration.

FIG. 9 is a top plan view thereof.

FIG. 10 is a bottom plan view thereof.

FIG. 11 is a front elevational view thereof.

FIG. 12 is a rear elevational view thereof.

FIG. 13 is a right elevational view thereof; and,

FIG. 14 is a left elevational view thereof.

The broken line showing is for environmental purposes only and forms no part of the claimed design.
